STOCKING

John Hamilton, Ivyland, Pa., assignor to Sanson
Hosiery Mills, Inc., Philadelphia, Pa., a corporation of Delaware

Application March 13, 1952, Serial No. 18,871

Term of patent 14 years

(Cl. D47—7)

To all whom it may concern:

Be it known that I, John Hamilton, a citizen of the United States and a resident of Ivyland, county of Bucks, State of Pennsylvania, have invented a new, original, and ornamental Design for a Stocking, of which the following is a specification, reference being had to the accompanying drawings, forming a part thereof, wherein:

Figure 1 is a side perspective view of the lower portion of the stocking, showing my new design; and

I claim:

The ornamental design for a stocking, substantially as shown.

JOHN HAMILTON.
